WINDOW MOVEMENT CONTROL SPRING

Luther V. Day, Gosport, Ind., assignor to National Tool and Die Company, Inc., Louisville, Ky., a corporation of Kentucky

Application June 12, 1947, Serial No. 754,098

6 Claims. (Cl. 292—76)

1

This invention relates as indicated to springs, but has reference more particularly to a spring of the leaf type which is especially adapted for controlling the movements of windows and the like.

A primary object of the invention is to provide a spring of the character described, which is extremely efficient in use, and highly effective for the purpose for which it has been designed.

Another object of the invention is to provide a spring of the character described, which is made from a single piece of sheet or strip metal, by simple and economical manufacturing operations, and which can be sold at an extremely low price and quickly and easily installed without the use of tools other than ordinary hand tools, such as a hammer.

A further object of the invention is to provide a spring of the character described, which can be used as an item of builder's hardware, for installation in both old and new buildings.

A still further object of the invention is to provide a spring of the character described, which can be easily and quickly adjusted to vary the tension thereof.

Other objects and advantages of the invention will be apparent during the course of the following description.

In the accompanying drawings, forming a part of this specification, and in which like numerals are employed to designate like parts throughout the same,

Fig. 1 is a front elevational view of a control spring embodying the invention;

Fig. 2 is a side elevational view of the spring, as viewed from the left side of Fig. 1;

Fig. 3 is a side elevational view of the spring, as viewed from the right side of Fig. 1;

Fig. 4 is a top plan view of the spring;

Fig. 5 is a bottom plan view of the spring;

Fig. 6 is a longitudinal cross-sectional view of the spring, taken on the line 6—6 of Fig. 1;

Fig. 7 is a longitudinal cross-sectional view of the spring, taken on the line 7—7 of Fig. 1;

Fig. 8 is a transverse cross-sectional view of the spring, taken on the line 8—8 of Fig. 1;

Fig. 9 is a fragmentary perspective view, illustrating the use of the spring in the lower window channel;

Fig. 10 is a fragmentary perspective view, illustrating the use of the spring in an upper window channel, and

Fig. 11 is a fragmentary perspective view illustrating the attachment of the spring to the edge of a window sash.

Referring more particularly to Figs. 1 to 8 in-

2

clusive, of the drawings, it will be seen that the control spring comprises a flat thin metal plate 1 having its ends rounded as at 2, and provided at its ends with perforations or holes 3, through which tacks or nails may be inserted for the purpose of securing the plate in place, as will be presently explained.

The plate 1 is stamped to provide tongues 4 and 5, which are identical in every respect, the tongue 4 extending longitudinally from one end of the plate, and the tongue 5 extending longitudinally from the opposite end of the plate, and in a direction opposite to that of the tongue 4. The tongue 4 is connected to the plate 1 as at 6, and the tongue 5 is connected to the plate 1 as at 7.

The tongue 4 is stamped outwardly to provide a portion 8 which extends at a slight angle to the plane of the plate 1, an intermediate flat portion 9, which lies in a plane substantially parallel with the plate 1, and an end portion 10, which also extends at a slight angle to the plane of the plate 1 and which terminates substantially in the plane of the plate 1. Similarly, the tongue 5 is stamped outwardly to provide a portion 11 which extends at a slight angle to the plane of the plate 1, an intermediate flat portion 12 which lies in a plane substantially parallel with the plate 1, and an end portion 13 which also extends at a slight angle to the plane of the plate 1 and which terminates in substantially the plane of the plate 1.

It will be further noted that the portion 8 of the tongue 4 increases in width as the point 6 of its connection with the plate 1 is approached, and that this widened portion overhangs to some extent the end 13 of the tongue 5. Similarly, the portion 11 of the tongue 5 increases in width as the point 7 of its connection with the plate 1 is approached, and this widened portion overhangs to some extent the end 10 of the tongue 4. Moreover, the portions 9 and 12 of the tongues 4 and 5 respectively lie in substantially the same plane, and are substantially parallel with each other.

By this construction and arrangement of the tongues 4 and 5, space is conserved, so that the spring can be made from as small a piece of metal as possible, and, at the same time, the areas of connection of the tongues with the plate 1 are made as long as possible, so as to decrease the likelihood of the tongues breaking off from the plate as the result of repeated flexures of the tongues relatively to the plate.

The tongues 4 and 5 constitute springs which are especially adapted for controlling or regulating the movements of windows in their channels, acting to take up any looseness between the win-

dows and the channels, and also acting to maintain the windows in adjusted position. Its use eliminates the use of sash cords, weights and pulleys.

In using the control springs in lower window channels, both windows are left in a closed position. One of the springs is then inserted between the window sash and the window channel, as shown in Fig. 9. The spring is then tapped downwardly, so that approximately the lower third of the spring extends below the plane of the upper rail of the window sash, and the upper end of the spring is then tacked in place. Another spring is then similarly positioned at the opposite side of the window. Upon raising of the lower window to its full extent, the lower ends of the springs will be exposed, and can be tacked or nailed to the window channels.

The spring tongues act to take up any loose play between the lower window and its channels, and thus serve to control or regulate the movements of the window, the window remaining in any desired position of adjustment. If the window is exceptionally loose, the tension of the springs may be adjusted by bending the tongues in a suitable manner. In the case of abnormally loose windows, a plurality of springs may be employed.

In using the control springs in upper window channels, the lower sash is raised to its highest point. One of the springs is then inserted between the window sash and the window channel, as shown in Fig. 10, and is tacked or nailed in place. Another spring is then similarly positioned at the opposite side of the window. Upon lowering the window sash to its full extent, the upper ends of the springs will be exposed, and can be tacked or nailed to the window channel.

In new buildings, before installation of the windows, the springs may be secured directly to each side of the upper sash, at a point about 6 inches below the top rail, as shown in Fig. 11. The springs may then be compressed, in order to set the sash in place. For the lower window, the same procedure is followed, the springs being placed on each edge of the sash about 6 inches from the top. The spring tension of the springs against the window channels will thus permit both windows to remain in any desired position. If the windows fit too tightly or too loosely, the tension of the springs can be adjusted by suitably bending the tongues thereof.

It is to be understood that the form of my in-

vention, herewith shown and described, is to be taken as a preferred example of the same, and that various changes in the shape, size and arrangement of parts may be resorted to, without departing from the spirit of my invention, or the scope of the subjoined claims.

I claim:

1. A spring for controlling the movements of windows, said spring comprising a metal plate having parallel transversely spaced tongues extending longitudinally from opposite ends of said plate, all portions of said plate, except for said tongues, lying in substantially a common flat plane, each tongue consisting of a plurality of angularly related portions, and each tongue being connected to the plate by a portion which increases in width as it approaches the plate.
2. A spring, as defined in claim 1, in which each tongue has a central flat portion which lies in a plane parallel with but spaced from the plane of the plate and in which the central flat portions of both tongues lie in substantially a common flat plane.
3. A spring, as defined in claim 2, in which each tongue has an end portion which extends angularly to the plate.
4. A spring, as defined in claim 3, in which one of the end portions of each tongue is connected to the plate and the other end portion of each tongue is unconnected to the plate.
5. A spring, as defined in claim 4, in which the end portion of each tongue which is connected to the plate overhangs the unconnected end portion of the other tongue.
6. A spring, as defined in claim 5, in which said plate has apertures in the ends thereof, adapted to receive fastening means.
